(57) **CLAIM**

We claim the ornamental design for a glove, as shown and described.

DESCRIPTION

FIG. 1 is a perspective view of a glove; FIG. 2 is a top view of the glove; FIG. 3 is a bottom view of the glove; FIG. 4 is a right-side view of the glove; FIG. 5 is a left-side view of the glove; FIG. 6 is a front view of the glove; FIG. 7 is a back view of the glove; and, FIG. 8 is a perspective view of the glove, shown in a state of use.

The broken lines depict portions of the glove and form no part of the claimed design. The additional broken lines in FIG. 8, depicting part of a person wearing shorts, show environment structure and form no part of the claimed design.

The glove is designed to receive two of a user's digits so that a cover portion of the article is positioned on the upper palm region of a user's hand. The glove may accessorize other items like shorts or towels, e.g., via snap-on or other attachment mechanism.
